Filed Apr. 11, 1961, Ser. No. 64,705

Term of patent 14 years

(Cl. D57—1)

FIG. 1

The rear of the sunglasses fronts not shown is substantially plain and conventional.

The dominant features of my design reside in the portions shown in full lines.

I claim:

The ornamental design for a sunglasses front or the like, substantially as shown and described.
